UNITED STATES PATENT OFFICE.

WILLIAM TONIE BRIDGES, OF LA FAYETTE, GEORGIA.

COMBINED THERMOSTATIC CIRCUIT CLOSER AND SPRINKLER.

Application filed June 10, 1922. Serial No. 567,392.

To all whom it may concern:

Be it known that I, WILLIAM T. BRIDGES, a citizen of the United States, residing at La Fayette, in the county of Walker and 5 State of Georgia, have invented a new and useful Combined Thermostatic Circuit Closer and Sprinkler, of which the following is a specification.

This invention relates to a combined 10 thermostatic circuit closer and sprinkler, and has for its object the provision of cooperating devices of improved construction for simultaneously sounding an alarm and causing a spray of water to be directed over a 15 predetermined area in concealed and obscure places affected by fire, which devices are automatically set in operation by the heat of combustion.

The invention will be best understood 20 from a consideration of the following detailed description taken in connection with the accompanying drawings forming part of this specification, with the understanding however, that the invention is not confined 25 to any strict conformity with the showing in the drawings, but may be changed and modified so long as such changes and modifications mark no material departure from the salient features of the invention as expressed in the appended claims.

In the drawings:—

Fig. 1 is a view in perspective of the combined circuit closer and fire extinguisher.

Fig. 2 is a vertical section of the same.

In the drawings a combined fire extinguisher and alarm are disclosed, cooperating with each other for simultaneous operation. The extinguisher comprises a water conduit 17 having a coupling member 18 with 35 a laterally extending nozzle 19, in which is mounted a rotary valve 20 for controlling the flow of water from the nozzle. The valve 20 is rotatably mounted within a valve casing 21 and adapted to be maintained in 40 open position by means of a coiled spring 22 surrounding the stem of said valve. A lever 23 is integrally formed with the stem of the valve, extended at right angles to said stem, and connected to a screw or lug 24 by means 45 of an easily fusible member 25 for maintaining the valve in closed position. One end of the coil spring 22 is secured to the lever 23, while the other end is connected to the 50 valve casing.

Upon the application of heat to the member 25, the same will be melted or burned

away and permit the spring 22 to rotate the valve 20 to open position, thereby alining the port 21^a in the valve casing with a passage in the nozzle 19 to permit a spray of 60 water to be forced upwardly and into engagement with a winged wheel 26 located in a horizontal position and mounted upon a threaded stud 27 which depends from a cup-shaped contact member 28. The winged 65 wheel 26, where rotatably mounted on the stud 27, is disposed between a washer and nut on the stud for maintaining the wheel in proper position relative to the spray of 70 water issuing from the port 21^a of the valve 75 casing.

The cup-shaped contact member 28 which supports the wheel 26 has a flanged portion 29 resting on the inner periphery of an opening in the concave portion of a housing 30. 75 Said housing may be of the type usually employed for enclosing the contacts for the push button of the ordinary electric house bell and which is mounted upon the jamb 80 of a front door.

The flange 29 of the contact member 28 is held in position against the periphery of the small lower central opening in the housing 30 by means of a spring 31 having one end seated in the cup-shaped contact member, with its other end pressing against a plate 32 centrally disposed within the housing 30 and secured in place by means of perforated upwardly-extending legs 33, the 85 perforations in the legs alining with the usual perforations in the housing 32, whereby said housing is secured by means of screws to the underside of the floor or ceiling of the building.

Spaced slots 34 are cut into the flange 35 of the housing 30 for the reception of the wires 4 and 6, which are connected with an alarm system, so that an alarm will be sounded when the wires are connected to each other. Secured on the upper side of the plate 32 is an insulating block 36 having spaced perforations alining with spaced perforations in the member 32 and through which is adapted to be screwed threaded studs 37. 95 The perforations in the slots through which the studs 37 pass are sufficiently enlarged to prevent current passing from the studs to said plate.

Between the head of the studs 37 and the 100 insulating member 36 are wound non-insulated portions 38 of the wires 4 and 6, so that when the threaded studs 37 are screwed

down into the insulating member 36, the wires will be securely held in spaced relation to each other. The lower end of the studs 37 provide contact members adapted to be engaged by the flange 29 of the cup-shaped circuit closer 28.

When sufficient heat has been developed in the neighborhood of the nozzle 19, the easily fusible retaining member 25 will be broken to release the arm 23 to permit the spring 22 to rotate the valve 20 and align the port 21^a with the passage in the nozzle 19, and thereby cause a spray of water under pressure to be forced against the winged wheel 26 and cause the wheel to be rotated and spray the water outwardly in all directions within a predetermined area. The pressure of the water in the nozzle 19 against the wheel 26 will overcome the pressure of the spring 31 and force the cup-shaped contact member 28 into engagement with the lower ends of the studs 37 and short-circuit the lead wires 4 and 6 at this point, and sound the alarm.

25. What is claimed is:

1. In a combined thermostatic circuit closer and sprinkler, main lead wires having portions disposed in parallel relation, a water conduit extending transversely of the parallel portions of the wire, nozzles connected with the water conduit at spaced points and provided with rotary valves for controlling the flow of water from said nozzles, a lever projecting from the stem of the valve, a coiled spring mounted on the stem of said valve and connected with the operating handle for maintaining the valve normally in open position, and easily fusible material connected with the handle and the nozzle for retaining the valve in closed position, a sprayer wheel adjacent the nozzle and adapted to be rotated by issuing water from the nozzle, spaced contacts connected with the parallel wires, and a movable contact held out of engagement with the spaced contacts and supporting the sprayer wheel, adapted to be moved into engagement with the spaced contacts by the pressure of the water from the nozzle.
50. 2. In a combined thermostatic circuit closer and sprinkler, main lead wires having portions disposed in parallel relation, a water conduit extending transversely of the parallel portions of the wire, nozzles connected with the water conduit at spaced points and provided with rotary valves for controlling the flow of water from said nozzles, a lever projecting from the stem of the valve, a coiled spring mounted on the stem of said valve and connected with the operating handle for maintaining the valve normally open, an easily fusible material for retaining the valve in closed position in opposition to the spring, a sprayer wheel adapted to be rotated by the water issuing from the

nozzle, spaced contacts connected with the parallel wires, a movable contact held out of engagement with the spaced contacts and supporting the sprayer wheel, adapted to be moved into engagement with the spaced contacts by the pressure of the water from the nozzle on the sprayer wheel, and a spring for maintaining the movable contact out of engagement with the spaced contacts.

3. In a combined thermostatic circuit closer and sprinkler, main lead wires having portions disposed in parallel relation, a cup-shaped housing secured to a fixed support and having a central opening, said lead wires having exposed portions passing through the housing, a plate secured centrally of said housing and adapted to support fixed contact members insulated from said plate and having connections with the wires, said housing being bent inwardly around said opening to form an annular seat, a movable contact member having a central cup-shaped portion extending through the opening, and a peripheral flange seated on said annular seat, a spring seated within the cup-shaped portion of the movable contact member and holding it normally in its outermost position, but yieldable to an external force applied to the convex face thereof to permit said peripheral flange to contact with the fixed contact members.

4. In a combined thermostatic circuit closer and sprinkler, main lead wires having portions disposed in parallel relation, a cup-shaped housing secured to a fixed support and having a central opening, said lead wires having exposed portions passing through the housing, a plate secured centrally of said housing and adapted to support fixed contact members insulated from said plate and having connections with the wires, said housing being bent inwardly around said opening to form an annular seat, a movable contact member having a central cup-shaped portion extending through the opening, and a peripheral flange seated on said annular seat, a spring seated within the cup-shaped portion of the movable contact member and holding it normally in its outermost position, a sprayer wheel journaled on the movable contact member outside the housing and normally spaced therefrom, and means operable under fire conditions to direct a stream of water under pressure against the sprayer wheel, and thereby force the peripheral flange of the movable contact member into contact with the fixed contact members.

5. In a combined thermostatic circuit closer and sprinkler, main lead wires having portions disposed in parallel relation, a housing secured to a fixed support, with the lead wires having exposed portions passing through the housing, a plate secured cen-

trally of said housing and adapted to support fixed contact members insulated from said plate and having connections with the wires, a movable contact member comprising a flanged cup-shaped member seated within a perforated concaved portion in the bottom of the housing, with the flange of the movable contact resting upon the periphery of the opening of the perforation in the housing, a spring having one end seated in the movable contact and its other end in engagement with the centrally disposed plate, and means active upon the melting of an easily fusible material to direct a force 10 against the movable contact to move the latter against the pressure of the spring into engagement with the spaced contacts and thereby close the circuit.

6. In a combined thermostatic circuit closer and sprinkler, main lead wires having portions arranged parallel to each other, a cup-shaped housing secured to a fixed support and provided with spaced contacts connected to each wire, said wires passing 25 through the housing, said housing having a central perforation in its bottom, a cup-shaped movable contact normally seated in said perforation in the bottom of the housing and out of engagement with the first-mentioned contacts, and means active upon the melting of an easily fusible material for directing a force against the last-mentioned contact member to cause it to engage the first-mentioned contact members and close 30 the circuit at this point.

7. In a combined thermostatic circuit closer and sprinkler, the combination of a relatively fixed cup-shaped housing having a central opening, a plate secured centrally

of said housing, fixed contact members supported by the plate and insulated therefrom, said housing being bent inwardly around its central opening to form an annular seat, a movable contact member having a central cup-shaped portion extending through the opening and having a peripheral flange normally seated on said annular seat, a spring seated within the cup-shaped portion of the movable contact member and adapted to hold it in its normal position, but yieldable 45 to an external force applied to the convex face thereof to permit said peripheral flange to contact with the fixed contact members.

8. In a combined thermostatic circuit closer and sprinkler, a relatively fixed cup-shaped housing having a central opening, a plate secured centrally of said housing, contact members secured to said plate and insulated therefrom, said housing being bent inwardly around its central opening to form 60 an annular seat, a movable contact member having a central cup-shaped portion extending through said central opening and having a peripheral flange normally seated on said annular seat, a spring within the 65 cup-shaped portion of the movable contact member outside the housing and normally spaced therefrom, and heat operated means to direct a stream of water under pressure against the sprayer wheel and thereby to 70 force the peripheral flange of the movable contact member into contact with the fixed contact members.

In testimony, that I claim the foregoing as my own, I have hereto affixed my signature. 75

WILLIAM TONIE BRIDGES.
